IDENTIFYING APPLIANCE

Filed Sept. 19, 1925

2 Sheets-Sheet 2

UNITED STATES PATENT OFFICE.

CHARLES S. RAILSBACK, OF COLORADO SPRINGS, COLORADO.

IDENTIFYING APPLIANCE.

Application filed September 19, 1925. Serial No. 57,445.

This invention relates to means for the identification of motor-driven vehicles and its primary object is to provide in connection with an appliance bearing a license number, factory number, name, date or other identifying matter, a means for fastening the same to a fixed part of the vehicle so that it cannot be removed except by irreparable destruction.

Another object of the invention is to provide by the use of an appliance of the above described character, means to prevent mutilation or alteration of the factory number of the vehicle which is usually stamped or cast in the motor block or other fixed part thereof. By the use of the invention, a legal transfer of a motor vehicle can be made only by the rightful owner of the car since it prevents fraudulent alteration of the number or other data that establishes the identity of the vehicle and thereby secures the purchaser against acquirement of stolen property.

The protective identification appliance may be affixed to the vehicle either by the manufacturer or under control of the state, county or municipality in which the vehicles are licensed and the invention includes two different forms operating on the same principle but individually adapted for the purposes above referred to.

In the accompanying drawings in which like characters of reference designate similar parts throughout the several views,

Figure 1 represents a perspective view of the invention in the form best adapted for application by the manufacturer of the vehicle;

Figure 2, a partially sectional side-elevation of the same, drawn to a reduced scale;

Figure 3, a longitudinal section of the construction shown in Figure 1;

Figure 4, a fragmentary section of an end portion of the device showing the identifying member thereof in its locked position on the relatively stationary member;

Figure 5, a transverse section taken on the line 5-5, in Figure 3;

Figure 6, a partially sectional plan view of the device in the form best adapted for application at the time the license under which the vehicle is operated, is issued by the proper authorities;

Figure 7, a longitudinal section of the device shown in Figure 6;

Figure 8, a perspective view of the device illustrated in Figures 6 and 7, drawn to a reduced scale;

Figure 9, a cross section on the line 9-9, Figure 7;

Figure 10, a partially sectional side-elevation of the device with the identifying part thereof in its locked position on the relatively stationary part;

Figure 11, a perspective view of a modified form of the stationary part of the device illustrated in Figures 6 to 10; and

Figure 12, a fragmentary longitudinal section along the line 12-12 in Figure 11.

Referring first to Figures 1 to 5, 2 designates a part of the motor block of an automobile, 3 a member of the appliance bearing the factory number of the car or engine, and 4 the protective identification member which normally is fastened upon the member 3 so that it can not be removed except by irreparable destruction.

The stationary member 3 has means for cooperation with a locking device to fasten the member 4 in the above stated manner but it is to be understood that while for convenience in manufacture, it is preferred to provide said means through the medium of a separately made member bearing the factory number and fastened upon the motor block, both the means and the number may be formed directly on the engine body in which case the identification member and the locking device are the only separate parts applied to the vehicle for the purpose of the invention.

The fixed member 3 of the appliance consists of an oblong bar 5 of dove-tail section and provided with an integral head 6 at one end, a recess 7 for the locking device adjacent its opposite end, and the factory number 8 formed in either raised or sunken figures in a lengthwise extending depression.

The member is fastened upon the motor block by bevel-headed screws 9 fitted in countersunk openings at opposite ends of the member.

The identification member 4 comprises a block having in its bottom surface a slide-way 10 of dove-tail section corresponding in form with the body portion of the fixed member, so that the one member may slide lengthwise upon the other member while being secured against vertical displacement.

The member 4 has between two solid end-ports, a longitudinal opening 12 to expose the number 8 on the stationary member and the opening is covered by a bar 13 extending

between the end-portions of the block in integral connection therewith and spaced from the sides of the block between said portions.

The sides of the bar and the corresponding edges of the sight-opening are beveled and rounded as best shown in Figure 5 in order to afford an unobstructed view of the number on the stationary member when the identifying member is in place thereon.

10 The bar 13 of the member bears on its upper surface a number 14 formed of cast or stamped figures, which corresponds with the factory number on the stationary member, and the corresponding surface of the 15 end portions of the block between which the bar extends, bears other identification matter as for example, the model of the automobile, the name of the vehicle or the name of the manufacturers thereof, the serial 20 number of the vehicle and other similar data all of which contribute to unmistakably establish the identity of the vehicle to which the invention is applied.

It is furthermore of advantage to form in 25 raised or sunken characters, a name or number along the edges of the block at opposite sides of its sight-opening, as at 15, so that said edges cannot be filed down to afford access to the number on the stationary member for fraudulent alteration, without immediate detection.

The block has on its underside a shouldered recess 16 which normally registers with the recess 7 of the stationary member as shown in 35 Figure 4, and it has furthermore a longitudinal depression 17 spaced from the recess 16 to permit of sliding the block upon the stationary member without undue tensioning of the locking member.

40 The locking member above referred to consists of a preferably V-shaped catch 18 of spring-metal which lies loosely in the recess 7 of the stationary member and projects above the upper surface of the body portion 45 of the same.

When the block is slid upon the stationary member the projecting end of the catch extends in the depression 17 in the bottom of the block and thus does not interfere with 50 the movement of the block until it engages the ridge between the depression 17 and the recess 16 when by continued movement of the block it is momentarily depressed and contracted by the contact of the ridge after 55 which it springs into the recess and thereby locks the block against backward motion. Further forward movement of the block is prevented by the head 6 on the stationary member 3, which is engaged by the end of 60 the block at the time the spring enters the recess of the same.

The above described form of the invention is particularly suited for use by the manufacturers of motor vehicles to safeguard their 65 customers against theft, although with

slight alterations, the device as shown may also be used by government officials at license-bureaus to protect the owners of licensed cars.

For the last mentioned purpose, however, the form of the invention illustrated in Figures 6 to 10 is better adapted since it includes the use of a locking device which performs the function of a license and can be obtained at little expense.

The modified construction comprises a 75 member 3 fixed on the motor body or other stationary part of the automobile, bearing the factory number and identical to the corresponding member of the first described form with the exception that the recess 7 80 is eliminated and the head 20 of the bar 19 is provided with a slot 21 for the application of the locking device as will hereinafter be described.

The bar 19 is as before, secured by screws 85 to the motor block and it is of dove-tailed section for the application of the block 4 by which the factory number is covered.

The block of the modified form of the invention is similar to that of the first described 90 construction in that it has a dovetailed groove in its bottom surface for co-operation with the correspondingly shaped body of the fixed bar, and in that it bears upon its upper surface, a duplicate of the factory number as 95 it appears on the member 3.

The block furthermore resembles the other in that it has a bar between two end portions, which is spaced from the sides of the body portion of the block to provide openings through which the number on the stationary member of the device may be observed.

One of the end portions of the block, however, is enlarged to form a hollow head 22 100 provided with a slot 23 which when the sliding block member 4 is in place on the relatively stationary member 3, is in alignment with the slot 21 in the head of the latter.

The hollow of the head on the block member provides a pocket or chamber 24 for the lock of the device by which the two members are secured against separation and it has a slanting surface to facilitate the insertion of the lock.

The locking device hereinbefore referred to, consists of a seal of the type commonly used in locking the doors of freight cars. It is composed of a pliable metal strap 25 fastened at one end to a housing 26 which contains a lock mechanism adapted to secure the apertured free end of the strap after the latter has been doubled and its end has been admitted to the lock mechanism through a slot in the housing.

For the purpose of the present invention, the pliable strap is stamped to bear certain identification matter, as for example, the license number of the vehicle as shown at 27, and the name of the state and the year dur- 100

ing which the license is valid as indicated at 28 and 29.

The seal is applied to the protective identification appliance by inserting its lock in the 5 chamber 24 and passing its strap through the alined slots 23 and 21. The block member is then slid upon the relatively stationary member until its end engages the head 20 after which the strap is doubled over the top of the 10 head and inserted through the slot of the head 22 on the block, into the therewith alined opening of the lock-casing contained in the chamber or pocket 24.

The lock mechanism of the seal includes a 15 member which enters the aperture in the free end of the strap and permanently fastens the strap in the lock so that the seal can not be removed without cutting and destroying the strap.

Owing to the fixed distance between the 20 heads of the two members of the appliance, the strap of the seal is readily proportioned so that after its application in the above described manner, it will be stretched taut and thereby prevent of the seal being reused with a shortened strap after the latter has been severed for removal of the movable part of the device for the purpose of fraudulently altering the factory number of the car.

It will be apparent that in both forms of 25 the invention the factory number on the engine block of the automobile is covered by the block so as to render it inaccessible for alteration; that the openings in the block permit of 30 reading the factory number on the engine at any time to compare it with the corresponding number on the block, and that the locking device in either case prohibits the removal of the member which covers the factory number, 35 without irreparable destruction of an essential and irreplaceable element of the appliance.

In order to further guard against fraudulent alteration or mutilation of the number 40 on the motor block, the numbers may be cast or stamped in depressions of the bar, divided by protective ribs 30 as illustrated in Figures 11 and 12.

It will be evident that the use of the invention 45 prevents alteration or mutilation of the car-number with fraudulent intent since the original number on the engine body is inaccessible to tools and since moreover it must correspond with the number of the protective member by which it is covered.

The cover member of the form illustrated 50 in Figures 1 to 5 can not be removed without irreparable destruction and in the modified form it can not be separated from the relatively stationary part without destruction of the seal which bears the license number, the name of the state and other identification marks.

The last mentioned form has the further 55 advantage of constituting definite proof of

the ownership of the vehicle by the records of the government under which the license for the operation of the car was issued.

It follows that a car identified by the use 60 of my invention in either form can be sold only by the person in whose name the property is recorded and that any attempt to dispose of the property by a person other than the rightful owner will lead to immediate discovery of the deceit.

While my invention as herein described and illustrated in the drawings is particularly adapted for use in connection with motor vehicles, it may if so desired be also used 65 for sealing gas meters and other devices identified by a serial number and requiring protection against unauthorized manipulation, adjustment, inspection or removal.

What I claim and desire to secure by Letters Patent is:

1. An identifying appliance comprising an element bearing an identifying mark, a member having a bar portion covering the identifying mark and openings at the sides thereof through which the mark may be seen, and a locking device permanently securing the member upon said element.

2. An identifying appliance comprising an element bearing an identifying mark, a member having a bar portion covering the identifying mark, an opening at a side thereof, through which the mark may be seen, and an identifying mark along an edge of the opening to prevent of its being widened without detection, and a locking device permanently 95 securing the member upon the element.

3. An identifying appliance comprising a member composed of a body part formed to provide a guide-way, and a head at an end of the body part, the member bearing an identifying mark upon its body part, means to secure the member upon a fixed part of an engine or the like, a second member adapted to slide in the guide-way of the first member and including a bar portion adapted to cover the identifying mark, and an opening at a side thereof through which the mark may be seen when the second member occupies a position determined by the head on the first member, and a locking device permanently securing 105 the second member upon the other.

4. An identifying appliance comprising a member composed of a body part formed to provide a guide-way, and a head at an end of the body part, the member bearing an identifying mark upon its body part, means to secure the member upon a fixed part of an engine or the like, a second member adapted to slide in the guide-way of the first member and including a bar portion adapted to cover the identifying mark, and an opening at a side thereof through which the mark may be seen when the second member occupies a position determined by the head on the first member, and a locking device permanently securing 110 120 125 130

the second member upon the other, the second member bearing identifying data including a mark corresponding with that on the first member.

5. An identifying appliance comprising an element bearing an identifying mark and having an apertured head, a member normally occupying a position relative to said element in which the identifying mark is covered, and having a pocket open at its underside, and a seal having a lock in said pocket and a pliable strap bent around the apertured head and having its end secured by the lock.

6. An identifying appliance comprising an element bearing an identifying mark, and having an apertured head, a member having a body part adapted to cover the identifying mark and bearing a corresponding mark and having opposite to the head, a pocket open at its underside, and a seal having a lock in said pocket, and a pliable strap extending over the body part of the member and bent around the apertured head with its ends secured by the lock.

25. 7. An identifying appliance comprising an element having an apertured head, a member normally occupying a determinate position relative to said element and having a pocket open at its underside, and a seal having a lock in said pocket and a pliable strap bent around the apertured head and having its ends secured by the lock, said strap bearing identifying matter which is visible when the appliance is in normal position.

35. 8. In an identifying appliance, the combination with an engine block bearing an identifying mark, a member having a sliding connection with the block and covering the mark in its normal position, and means, including

an inaccessible lock, preventing the member from being slid from said normal position.

9. An identifying appliance comprising an element containing an identifying mark, a member having an integral part covering the mark on the element and having an opening adjacent said part through which the mark can be seen, and means, including a lock, enclosed by said member, to fasten the member in position on the element, the lock being inaccessible except by breaking the member.

10. An identifying appliance comprising an element bearing an identifying mark, a member having a bar portion covering the mark and having an opening at a side thereof through which the mark may be seen, and a locking device securing the member upon said element.

11. An identifying appliance comprising in combination with an element bearing an identifying mark, a member normally occupying a position relative to said element, in which the identifying mark is covered, and a seal locking the member in its said position on the element and composed of a doubled strap bearing identification matter, and a lock, enclosed by said member, securing the ends of the strap.

12. An identifying appliance comprising an element having an identifying mark, a member covering said identifying mark and having an opening out of direct alinement with the mark, through which the mark may be seen, and means for securing the member against its removal without detection.

In testimony whereof I have affixed my signature.

CHARLES S. RAILSBACK.
